Primary Examiner — Wan Laymon*Assistant Examiner* — Clint A Samuel(74) *Attorney, Agent, or Firm* — Willis IP; Ryan Willis(57) **CLAIM**

I claim the ornamental design for a haggis link, as shown and described.

DESCRIPTION

FIG. 1 is an isometric view of an exemplary haggis link design in accordance with the present design.

FIG. 2 is a bottom view of the exemplary haggis link design shown in FIG. 1.

FIG. 3 is a left profile view of the exemplary haggis link design shown in FIG. 1.

FIG. 4 is a right profile view of the exemplary haggis link design shown in FIG. 1.

FIG. 5 is a rear view of the exemplary haggis link design shown in FIG. 1.

FIG. 6 is a front view of the exemplary haggis link design shown in FIG. 1; and,

FIG. 7 is a cross-sectional view of the exemplary haggis link design shown in FIG. 1 taken along the dotted line 7-7.
